UNITED STATES PATENT OFFICE.

GEORGE STEPHEN POLLEY, OF ASHTABULA, OHIO.

TEETER-BOARD.

1,209,881.

Specification of Letters Patent. Patented Dec. 26, 1916.

Application filed July 5, 1916. Serial No. 107,628.

To all whom it may concern:

Be it known that I, GEORGE S. POLLEY, a citizen of the United States, residing at Ashtabula, in the county of Ashtabula and State of Ohio, have invented a new and useful Teeter-Board, of which the following is a specification.

The present invention appertains to teeter boards or seesaws, and aims to provide a novel and improved device of that character.

It is the object of the invention to provide a teeter board or seesaw which is substantial in construction and which is adjustable to various vertical heights.

Another object of the invention is the provision of a teeter board having novel means for controlling the equilibrium and operation thereof, whereby to enhance the utility of the device for the amusement, entertainment and exercise of children.

A further object of the invention is the provision of novel means for counter balancing the device when the persons at the opposite ends are of different weights.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a side elevation of the improved teeter board. Fig. 2 is a diagrammatical side elevation illustrating the lever arrangement for the over balancing weight. Fig. 3 is a fragmental plan view of the device, portions being removed. Fig. 4 is a vertical section taken on the line 4-4 of Fig. 3. Fig. 5 is a detail view illustrating a means for adjusting the axle vertically.

The teeter board proper or rocking member embodies a pair of longitudinal bars 1, which are mounted intermediate their ends upon a pipe or tubular bearing member 2 disposed transversely and mounted for rotation upon a transverse axle rod 3 terminally supported by a pair of standards or posts 4 carried by a suitable base 5. The standards 4 have vertical series of apertures 6 for the

reception of the terminals of the axle rod 3, whereby the axle rod can be adjusted vertically for supporting the teeter board in various vertical positions. The bars 1 are connected by tie rods 7 and have disposed therebetween spreaders or spacers 8 against which the bars 1 are clamped by the tie rods 7, and braces 9 are preferably disposed between the bars 1 for reinforcing the structure.

In order to truss the bars 1, vertical bars or truss members 10 are fitted upon and secured to the bars 1 intermediate their ends and adjacent the axle, as at 11, and the lower ends of the bars 10 are connected by a cross piece or yoke 12. The bars 10 are connected adjacent their upper ends by tie rods 13 and a spreader or spacer 14 is disposed between the bars 10 adjacent their upper ends. Truss rods or elements 15 connect the upper end portions of the bars 10 with those portions of the bars 1 adjacent the ends thereof, and similar truss rods or elements 16 connect the bars 1 adjacent their ends with the lower ends of the bars 10. The truss elements 15 and 16 can be rods, wire, or the like, and in connection with the bars 10 serve to thoroughly truss the rocking member.

Suitable seats 17 are disposed between the opposite ends of the bars 1 and are pivoted or fulcrumed thereto, as at 18, and said seats are provided with backs 19 and with depending arms 20. The arms 20 are connected by the links 21 with the lower arms of pairs of levers 22 fulcrumed or pivoted, as at 23, to the bars 1 in front of the seats 17 which face toward the center of the structure. Foot boards 24 are secured upon the links 21 and provide a foot rest for each seat 17. The seats and levers 22 are thus linked together to swing in parallelism. The pairs of links 21 are connected by pairs of links 25 with pairs of levers 26 fulcrumed, as at 27, to the bars 1 between the seats and center of the structure. A pendulum 28 is mounted loosely upon the tubular bearing 2 between the bars 1 for swinging or rocking movements between said bars toward and away from the seats, and the upper and lower arms of the pendulum 28 are connected by links 29 with the levers 26. The lower end of the pendulum 28 carries a suitable over-balancing weight 30 controlled by the seats 17 and levers 22.

Buffer springs 31 are preferably secured to the ends of the bar 1 to contact with buffer plates 32 upon the ground or floor, whereby to avoid shocks due to the ends of 5 the board striking the ground or floor.

As a means for obtaining the balance of the rocking member should the persons seated upon the seats 17 be of unequal weights, a pair of tanks 33 for holding 10 water or other liquid is mounted between and carried by the bars 1, said tanks being carried by the opposite arms of the rocking member at opposite sides of the fulcrum or axle thereof. The bottom portions of the 15 tanks 33 are connected by a pipe 34 provided with a valve 35 having the controlling arm 36, and cords or other operating elements 37 are attached to said arm 36 and extend to the seats, being preferably connected to certain of the levers 22 whereby 20 the cords can be readily grasped for operating the valve. The tanks 33 are partially filled with water or other liquid, and to balance the rocking member, this can be 25 done when the lighter arm thereof is lowermost, by opening the valve 35 to permit the water to flow from the uppermost to the lowermost tank until a balance is obtained, in which event the valve 35 is closed. Said 30 valve can be readily operated from the seats 17 by means of the cords 37.

As a convenient means for adjusting the axle to raise or lower the rocking member, straps 38 are secured upon the upper ends of 35 the standards 4 and are provided with seats 39 for a shaft 40 upon which cables 41 are secured and adapted to be wound. Said cables 41 have hooks 42 engageable with the axle, and the shaft 40 has a crank 43 at one 40 end whereby it can be rotated by either winding the cables upon or unwinding them from the shaft 40 for raising or lowering the axle. The shaft 40 can be readily applied to the standards, and when its use has 45 passed, it can be readily removed.

In operation, supposing the children to be seated upon the seats 17, with the rocking member properly balanced, when the rocking member is in horizontal position, the 50 pendulum 28 will be in vertical position, with the over-balancing weight 40 below the axle of the rocking member, and with the levers 26 and 22 as well as the arms 20 vertical. The equilibrium of the rocking member is destroyed by the movement of the 55 weight 30, assisted by the movements of the operators in the ordinary manner. Thus, supposing that the foot boards 24 at the left hand end are moved inwardly while the foot 60 boards at the right hand end are moved outwardly, the motion will be transmitted by means of the links 25, levers 26 and links 29 to the pendulum 28, and the over-balancing weight 30 will be moved toward the left, thus over-balancing the left arm of the 65

rocking member, whereby the left arm will swing downwardly to raise the right arm, it being noted, in this connection, that during this movement of the rocking member, the left hand seat 17 will swing outwardly, 70 while the right hand seat will swing inwardly so that the shifting of the bodies of the operators will assist in the swinging movement of the rocking member. Now when the rocking member reaches the end 75 of such movement, the movement of the foot boards 24 is reversed, and they are shifted toward the left, thereby moving the counter balancing weight 30 to the right, and the seats 17 swinging toward the right, will 80 shift the greatest weight to the right arm of the rocking member, whereby to check the movement of the rocking member, to avoid a sudden jar by the left arm thereof striking the ground, and the movement of the 85 rocking member will be reversed so that the right arm moves downwardly while the left arm is raised. Thus, by the operation of the foot boards 24, the rocking member is tilted first in one direction and then in the other. 90 The operation of the over-balancing weight can be conveniently effected by the operators resting against the backs of the seat and pushing with their feet against the foot boards 24, to swing the backs 19 outwardly 95 and force the foot boards 24 inwardly, and the operators can grasp the upper arms of the levers 22 to swing said levers to assist in the operation of the device.

The ends of the rocking member can be 100 provided with extra seats if desired, and the rocking member can be provided with a running board extending from one seat to the other for convenience in permitting the children to conveniently mount the device. 105

Having thus described the invention, what is claimed as new is:

1. A teeter device embodying a pair of standards, a vertically adjustable axle carried thereby, a rocking member mounted between its ends upon said axle, the upper ends of said standards having seats, a winding member seatable in said seats, and cables attached to said winding member and having means for engaging the axle, said winding member being removable.

2. A teeter device embodying a rocking member fulcrumed between its ends, seats movably carried by the ends of said member, an over-balancing weight movable toward and away from the ends of said member for over-balancing the arms thereof, and means for operatively connecting said weight and seats.

3. A teeter device embodying a rocking member fulcrumed between its ends, seats carried by the ends of said member, a pendulum having an over-balancing weight and mounted adjacent the fulcrum of said member, said weight being movable toward and 130

- away from the ends of said member, and
means for operating said pendulum from
the seats.
4. A teeter device embodying a rocking
member fulcrumed between its ends, seats
pivoted to said members adjacent the ends
thereof, an over-balancing weight movable
toward and away from the ends of said
member, and operative connections between
10 said seats and weight for moving it.
5. A teeter device embodying an axle, a
rocking member mounted upon the axle be-
tween its ends, seats pivoted to said member
adjacent the ends thereof, a pendulum car-
15 ried by said axle and having an over-bal-
ancing weight movable toward and away
from the ends of said member, and opera-
tive connections between said seats and
pendulum.
- 20 6. A teeter device embodying a rocking
member fulcrumed between its ends, an over-
balancing weight movable toward and away
from the ends of said member, seats pivoted
to said member adjacent the ends thereof
- and having downwardly projecting arms, 25
levers pivoted to said members adjacent the
seats, foot rests pivotally connected with
said arms and levers, and operative connec-
tions between said foot rests and weight.
7. A teeter device embodying an axle, a 30
rocking member mounted between its ends
upon said axle, a pendulum carried by said
axle and having an over-balancing weight
movable toward and away from the ends
of said member, seats pivoted to said mem- 35
ber adjacent the ends thereof and having
downwardly projecting arms, levers piv-
oted to said members adjacent the seats,
foot rests pivotally connected with said arms
and levers, and operative connections be- 40
tween said foot rests and pendulum.

In testimony that I claim the foregoing
as my own, I have hereto affixed my signa-
ture in the presence of two witnesses.

GEORGE STEPHEN POLLEY.
